UNITED STATES PATENT OFFICE.

JOHN O'DONNELL, OF RUTHERFORD PARK, NEW JERSEY.

BALL-COVER.

SPECIFICATION forming part of Letters Patent No. 240,327, dated April 19, 1881.

Application filed October 26, 1880. (No model.)

To all whom it may concern:

Be it known that I, JOHN O'DONNELL, a citizen of the United States, residing at Rutherford Park, in the county of Bergen and State of New Jersey, have invented and produced a new and useful Improvement in Ball-Covers, of which the following is the specification.

My invention consists in certain novel improvements in the method of covering the ball proper, and in the shape of the leather forming said covering, the object being to produce a ball-cover which will prevent the waste of leather necessary in stamping or cutting out any ball-cover now in existence, and save time and labor in sewing, the construction and application of which will be herein fully pointed out and described.

Figure 1 shows the drawing of one-half the cover, the two being similar in all their parts. Figs. 2 and 3 show the cover in different positions, as it appears on the ball.

The method of sewing on the cover is the same as in the ordinary ball, and needs no description here.

Heretofore the stamping or cutting out of 25 the trifurcated or other covers caused great waste of leather.

My improvement saves one-half the leather which is now thrown away, and the time and labor saved in sewing is one-third less than 30 any ball-cover patented, which is a desideratum in the manufacturing of base-balls, and never before attained.

Having fully described my invention, what I claim as new, and desire to secure by Letters Patent, is—

A cover for balls, composed of two pieces of leather cut into the shape shown, so as to prevent the waste of leather in stamping or cutting out, and to save time and labor in sewing, 40 as herein set forth.

JOHN O'DONNELL.
